OR D18,590 EX.

DESIGN.

—o—

K. STACHOWSKI.

BADGE.

No. 18,590.

Patented Sept. 4, 1888.

UNITED STATES PATENT OFFICE.

KASIMIR STACHOWSKI, OF CHICAGO, ILLINOIS.

DESIGN FOR A BADGE.

SPECIFICATION forming part of Design No. 18,590, dated September 4, 1888.

Application filed June 5, 1888. Serial No. 276,165. Term of patent 3½ years.

To all whom it may concern:

Be it known that I, KASIMIR STACHOWSKI, a subject of the Emperor of Germany, residing at Chicago, in the county of Cook and State of Illinois, have invented and produced a new and original Design for a Society Badge, of which the following is a specification, reference being had therein to the accompanying photographic illustration, forming part thereof.

The nature of my invention is fully represented in the accompanying drawing, to which reference is made.

The photographic illustration represents a magnified face view of the badge.

This badge-medal is in form of a Maltese cross, with a medallion in relief upon the center and with the ends of its arms being curved and beaded. Upon its medallion having a beaded border is the portrait of Saint Maria and the child Jesus, each within a circle of

glory. Upon the upper arm of the cross is a burning heart, upon the left arm the eagle of the Poland coat of arms, upon the right arm a knight in armor on horseback, and upon the lower arm a standing angel holding a sword in his right hand and the tablet with the Ten Commandments with his left hand. Upon the upper arms is space for any suitable letters or inscription.

What I claim is—

The design for a badge-medal, consisting of a Maltese cross with a medallion center in relief and with the ends of its arms curved and beaded, the whole being ornamented as shown and described.

In testimony whereof I affix my signature in presence of two witnesses.

KASIMIR STACHOWSKI.

Witnesses:

WILLIAM H. LOTZ,
OTTO LUBKERT.
